ELMER E. SHAFER, OF BENTON COUNTY, IOWA.

ROTARY VALVE FOR ENGINES.

1,091,541.

Specification of Letters Patent. Patented Mar. 31, 1914.

Application filed April 12, 1913. Serial No. 760,686.

To all whom it may concern:

Be it known that I, ELMER E. SHAFER, a citizen of the United States of America, and a resident of Benton county, Iowa, have invented certain new and useful Improvements 5 in Rotary Valves for Gas-Engines, of which the following is a specification.

My invention relates to improvements in rotary valves for gas engines, and the object 10 of my improvement is to supply for such engines, and particularly for engines having a plurality of cylinders, means for controlling the admission and exhaust to and from said cylinders, and the invention consists in 15 the novel construction and combination of the parts hereinafter fully described and claimed.

In the drawings, Figure 1 is a side elevation of a multi-cylinder internal-combustion engine as equipped with my improved controlling means for the admission to and the 20 exhaust from its cylinders. Fig. 2 is a vertical transverse section on a larger scale of one of the conical plug-valves with its chamber and other parts of the engine, with parts 25 broken away. Fig. 3 is a horizontal axial section of the valve-chamber and the valves therein. Fig. 4 is a perspective detail view of one of the conical plug-valves. Fig. 5 is 30 a transverse section of one of the conical plug-valves, showing the relative dimensions of its ports and the intervening solid parts of the valve.

Similar numerals of reference denote 35 responding parts throughout the several views.

It is my object herein, to do away with the necessity of puppet-valves with their 40 springs, and adopt other means for controlling the admission to and the exhaust from the cylinders of an internal-combustion engine, which will be self-clearing, and self-fitting, and will perfectly accomplish the functions mentioned. With this end in 45 view, I have adopted the construction of valves shown in the figures, and referring especially to Figs. 2 to 5 inclusive, which show the form and mounting of said valve.

In Fig. 1, which shows a multi-cylinder 50 engine having the cylinders 11, 12, 13 and 14, whose piston-rods are operatively-connected with a common crank-shaft 28, a like plurality of spaced valve-chambers 6 of conical form are in communication with said 55 cylinders respectively, by way of a port in each valve-chamber. Each valve-cham-

ber 6 is separately constructed from the other valve-chambers, and has at its diminished end an outwardly-turned flange ring 18 supplied with a plurality of orifices adapted to receive the screws 19, the latter having their ends secured in interiorly-threaded sockets in the abutting edges of the next valve-chamber. In the upper part of each valve-chamber is formed an oil-chamber 7 in communication with the hollow of the chamber, the latter being coned to fit the conical valve 1, the latter being a frustum of solid metal having a square axial orifice 35 adapted to receive a square spindle 34 to rotate therewith, the valve being movable therealong. Since the valve 1 fits the conical seat in the valve chamber 6, it will in time wear its peripheral bearing surface as well as the bearing surface of the chamber, and I have adopted means for taking up for this wearing to at all times provide a tight well-fitting joint between said parts.

The numeral 21 denotes a pin seated removably in a transverse orifice in the spindle 80 34, and the numeral 20 denotes a coiled compression-spring seated about said spindle and engaged between said pin and the adjacent wider head of the valve 1, and the spring acts to retain the valve on its seat and take 85 up wear. Each valve 1 is supplied with a like installation of spring and mounting, when used with a multi-cylinder engine, and each valve-chamber 6 has on opposite sides like inlet- and exhaust-ports 30 and 31 90 which open respectively into the inlet-pipes 32 of the carbureter and into the pipes 33 of the exhaust-chamber. On one end of the spindle 34 is fixed a ring 22, and an annular web 23 of a casing 27 lies abutting thereon, 95 both said parts having counterpart raceways for anti-friction balls 24, thus providing an anti-friction bearing to take up end-thrust. A sprocket-wheel 25 is secured on the spindle 34, and a sprocket-chain 26 operatively 100 connects said wheel with another sprocket-wheel 29 on said crank-shaft 28, the said wheels being of dimensions adapted to rotate the spindle and said valves a one-half 105 rotation during each rotation of the crank-shaft.

In each valve 1 is provided a cross-passage 3, through one side thereof, and the width of said passage is throughout one eighth of the circumference of the valve, that is, each 110 end of said passage is of that width, and the solid part of the valve between these pas-

sage-ends is also in width one eighth of the circumference of the valve, which leaves the remainder of the solid part of the valve between the passage-ends oppositely, of a 5 width of five-eighths of the circumference of the valve. These proportions are important for reasons to be hereinafter specified. In the rotation of said spindle and valves to control the admission and exhaust of said 10 cylinders, the valves are rotated continuously, and the transverse passage 3 of each valve is placed alternately to cause the admission-port and then the exhaust-port to be placed in communication with the combustion-chamber of the cylinder. The small 15 solid part of the valve which lies between the passage-ends 3 is of a width just sufficient to permit of the rotation of the valve while the piston of the engine is in its stationary condition between two cycles, and so that the passage-ends will register with the cylinder port 5 at the right times for admission or exhaust respectively. The 20 valve-chambers may be separately removable from the cylinders, by providing them with flanges 9 which are orificed to take screws 8, the latter working in interiorly-threaded sockets in the projecting parts 10 of the cylinders.

Having described my invention, what I 25 claim as new, and desire to secure by Letters Patent, is:

1. The combination, with a plurality of cylinders, of a separate valve-chamber for 30 each cylinder, a conical plug-valve working in and fitted to each valve-chamber, means for holding each plug-valve in contact with its seat, each valve-chamber having inlet and

exhaust passages for its communicating cylinder, and each valve having a passage extending through one side portion of it and operating to place the passage thereof alternately in communication with its respective cylinder. 40

2. The combination, with a plurality of cylinders, of a separate valve-chamber for each cylinder, a conical plug-valve working fittingly in each valve-chamber and provided with a hole at its axis in line with the like holes in the other valves, separate 50 means for holding each valve in contact with its seat, and a rotatable driving-spindle extending through all the said holes in said valves and operating to rotate the valves and permitting each valve to slide longitudinally independently of the other valves. 55

3. The combination, with a plurality of cylinders, of a separate valve-chamber for each cylinder, a conical plug-valve working fittingly in each valve-chamber and provided with a hole at its axis and a tubular stem at its smaller end, a spring connected to each said valve and operating to hold it to its seat fittingly, independently of the other valves, and a rotatable driving-spindle extending through all the axial holes of said valves and operating to rotate the valves and permitting each valve to slide lengthwise therealong independently. 60 65

Signed at Garrison, Ia., this 26th day of March, 1913.

ELMER E. SHAFER.
